UNITED STATES PATENT OFFICE.

CARL B. NEHLS, OF DETROIT, MICHIGAN, ASSIGNOR TO FELT-SUB POLISHING WHEEL COMPANY, OF DETROIT, MICHIGAN, A PARTNERSHIP CONSISTING OF EDWARD GESSER, BARNEY NEHLS, FRANK SHIELDS, AND CARL B. NEHLS.

BUFFING OR POLISHING WHEEL.

1,195,389.

Specification of Letters Patent. Patented Aug. 22, 1916.

Application filed September 9, 1915. Serial No. 49,705.

To all whom it may concern:

Be it known that I, CARL B. NEHLS, a citizen of the United States of America, residing at Detroit, in the county of Wayne and State of Michigan, have invented certain new and useful Improvements in Buffing or Polishing Wheels, of which the following is a specification, reference being had therein to the accompanying drawings.

10 The invention relates to buffing or polishing wheels, and it is the primary object of the invention to obtain a more resilient construction in which the work can be performed with less fatigue to the operator.

15 To this end the invention comprises the novel construction as hereinafter set forth.

In the drawings: Figure 1 is a section through the wheel in the axial plane thereof; Figs. 2 and 3 are side elevations of two of 20 the disks inclosing the wheel; and Fig. 4 is a similar view showing a modified construction.

My improvement belongs to buffing or polishing wheels of the type in which a series of disks formed of rags or other fabric are glued together and are peripherally sized and coated with the abrasive material. In the use of such wheels it has been found that when first made they are not adapted for 25 fine work, so that it is customary to first use them upon coarse work until they become more yielding. Furthermore, on account of the rigid character of the wheels, the work performed thereon is more fatiguing to the 30 operator. With my improved construction the initial rigidity of the wheel is overcome, and furthermore a greater degree of resiliency is imparted thereto than with constructions heretofore used.

40 Broadly described, my improvement comprises the cutting away of portions of the disks so as to lessen the rigidity thereof. Preferably the disks are alternately partially cut away and left imperforate, the imperforate members retaining the form of the

45 wheel while the cut-away members impart the yielding character. Thus, as shown in

Fig. 1, A A', etc., are imperforate disks, and intermediate these disks are partially cut-away disks B B' etc. The disks may be cut-away centrally, as indicated at C, Fig. 3 or in segments D or a series of apertures E, as shown in Fig. 4. In each case the rigidity of the structure is lessened and the resiliency increased.

55 In assembling the parts they may be mounted upon an arbor or shaft F and secured by gluing and by clamping collars G, as shown in Fig. 1. The peripheral portions of the disks are then sized and coated with 60 the abrasive material, after which they are in condition for use.

55 In operation it has been found that wheels constructed in the manner above described may at once be used upon fine work and on 65 account of their resilient nature lessen the fatigue to the operator.

The disks may be formed of any suitable material, such as rags with fabric facings, secured by a spiral line of stitching H, as 70 shown in Fig. 2.

What I claim as my invention is:

1. A buffing-wheel, comprising a body formed of a series of fabric disks of substantially uniform diameter, forming a continuous cylindrical surface, portions of said disks being cut-away to increase the resiliency.

75 2. A buffing-wheel, comprising a series of fabric disks alternately imperforate and partially cut-away, and forming a continuous cylindrical surface.

80 3. A buffing-wheel, comprising a body formed of a series of fabric disks forming a continuous cylindrical surface, the peripheral portions of all of said disks being imperforate, and portions of alternate disks within the periphery being cut-away.

85 In testimony whereof I affix my signature in presence of two witnesses.

CARL B. NEHLS.

Witnesses:

JAMES P. BARRY,
H. E. BOWMAN.
